United States Patent Office.

HENRY WARNER, OF NEWARK, NEW JERSEY.

Letters Patent No. 73,411, dated January 14, 1868.

IMPROVEMENT IN MACHINE FOR SIZING HAT-BODIES.

The Schedule referred to in these Letters Patent and making part of the same.

TO ALL WHOM IT MAY CONCERN:

Be it known that I, HENRY WARNER, of the city of Newark, in the county of Essex, and State of New Jersey, have made certain Improvements in Machines for Sizing Hats; and I do hereby declare the following to be a full and exact description of the same, reference being had herein to the drawings that accompany this specification, and which make part of the same.

The nature of my improvement consists in giving to the roll of the hat-body a motion similar to that of the hand, by peculiar devices, and in provisions in the machine which adapt it to the various kinds of material that may be used, and for wet or dry work, as the case may require.

In the drawings, A shows the frame; B, a triple crank; C, a movable board, secured to the two connecting-rods *z z*; D, an under sliding board, moved by the centre crank, and by the crooked connecting-rod *y*; and E, a broad trough to carry off the water. F shows a pair of expressing-rollers, G a hot-water, and H a steam-pipe, and I a weight on the upper moving board. The roll of hats is shown by *x*. The injection-box, for hot water or steam, is shown at *w*. It will be seen that, as the board C is fast to the connecting-rods, and rests upon the roll *x*, the cranks, when they move the board forward, tilt it, so that the hinder part is the lowest, thus giving a pushing force behind the roll, in addition to the rolling motion, and as soon as the cranks change the direction, they tilt down the forward edge of C, and continue the same pushing rolling motion in the backward rolling. Bars of various weight, placed as shown at I, are used to regulate the pressure. To the lower board, D, motion is given by the centre crank, the direction of the motion being the reverse of C. The working faces of the boards C and D are slightly corrugated, and, for some kinds of work, covered with cloth. By the weight I the machine can be adapted to every degree of light or heavy work, according to the nature of the material. The pipes G and H are respectively connected, at one end, to suitable supplying-sources for hot water and for steam, and the supply of either or both, to the box or chamber *w*, which distributes the same on the material, is regulated at will, as the operator may desire, in order to hasten or retard the felting process, by means of stop-cocks. By using the steam-pipe H only, I subject the material to the process known as the hot dry process, and by the employment of the water-pipe G, to the wet process. As the roll with the hat or hats frequently gets into a position not at right angles with the working boards, two uprights, *v v*, are constructed, as shown at J, which, being loose in the board C, can move up and down when the wheels in their lower extremities come in contact with the lower board D. These uprights bring the roll square with the boards, and keep it always in its work. A cord, *t*, fast to the upper board C, is led over suitable pulleys, and conducted to a position easily accessible to the operator, for him to lift and hold up the board C while he changes the roll for what is technically termed crossing, which is changing the position of the hat-body or bodies in the cloth which envelopes them, and the expressing-rolls F are used at the same time, when the hot wet work is being done.

What I claim as my improvement, and desire to secure, is—

1. The combination of the reciprocating rocking platen or board C, platen or board D, and connecting-rods *z y*, with the crank-shaft B, as and for the purpose described.
2. The injectors G and H, and the distributer *w*, when used in combination with the boards C and D, substantially as shown.
3. The expressing-rollers F and the weights I, when combined with the described sizing-machine, in the manner and for the purpose specified.

HENRY WARNER.
